2 SHEETS—SHEET 2.

UNITED STATES PATENT OFFICE.

JOHN B. BOLITHO, OF ROCKBEARE HOUSE, NEAR EXETER, ENGLAND.

AIM-RECORDING APPARATUS.

No. 926,541.

Specification of Letters Patent.

Patented June 29, 1909.

Application filed September 26, 1908. Serial No. 454,868.

To all whom it may concern:

Be it known that I, JOHN BRUCE BOLITHO, a subject of the King of Great Britain, residing at Rockbeare House, near Exeter, Devonshire, England, gentleman, have invented new and useful Improvements in Aim-Recording Apparatus, of which the following is a specification.

This invention relates to target practice and aim recording apparatus or the like where no projectile is employed.

Heretofore various apparatus and devices have been employed for indicating or recording the aim of a gun or rifle or simulated fire-arm, either upon the target at which the gun is aimed or (in some cases) upon a sub-target; but such apparatus have usually been complex and expensive and in the case of the apparatus which have been designed for following and indicating the aim of a rifle and recording the same on a sub-target, such apparatus has the further drawback that the rifle is so mounted, connected and arranged in the apparatus that the marksman has not the same freedom in using the rifle as he would have in the ordinary way with a rifle apart from any apparatus.

Now my invention is designed to provide not only a very simple and inexpensive target practice and aim recording means or the like where no projectile is employed but also has the further object that it enables the marksman or person using the same to have perfect freedom or practically perfect freedom in handling and aiming the rifle or gun or simulated fire-arm.

My invention comprises broadly; a small holder for holding the miniature target or so-called sub-target on which the aim is to be recorded; a small apparatus or simple means for pricking or otherwise marking said target at the moment of pulling the trigger, said apparatus or means being attached to the stock or side of the gun toward the butt end thereof, and in such position as not to interfere with the holding of the rifle in aiming; bearings or brackets laterally extending from the side of the gun; and a gyratory arm or rod mounted in each of the said bearings in suchwise as to be adapted to have a universal turning movement in said bearings. One of the said gyratory arms or rods carries the aforesaid sub-target holder and is flexibly jointed to one end of another or forward gyratory arm or rod. This last named rod is or may be connected to a long rod or tube,

which in turn is connected to the target proper at which the gun is to be aimed, and a connection is provided between the trigger and the sub-target marking apparatus to cause the latter to mark the sub-target at the moment when the trigger is pulled. The said long arm or connection may be a light metal rod (tubular or otherwise) and same may be attached at or toward the target end by a universal joint or other suitable attachment; and if desired this rod may be arranged to slide through a universal joint in order that there may be greater freedom of movement when the gun is aimed at the target, the gyratory movement of the muzzle of the gun in the act of aiming—or of bringing the gun into position to aim at the required part of the target—causes a corresponding gyratory movement of the gyratory end of the said long wire or connection from the target to the gun, and this last-named gyratory movement is imparted to the aforesaid gyratory arm or rod which latter carries the sub-target as aforesaid and to which latter in turn corresponding gyratory movement is imparted, and thereby the sub-target is gyrated or moved with respect to the marker or indicating device located close up to same, and the relative position of the marker and sub-target will correspond with the relative position of the gun with respect to the target proper so that at the moment the trigger is pulled an exact indication of the aim of the gun is thereby given and recorded on the sub-target. The respective gyratory movements imparted to (1) the muzzle of the gun (2) the ends of the gyratory arms or rods and (3) to the sub-target holder, will all correspond and synchronize but nevertheless may vary in relative extent of movement as required.

For the sake of example I will now describe my invention in detail with reference to the accompanying drawings as carried into practice with an ordinary service rifle.

Referring to the accompanying drawings:—Figure 1 is a view in side elevation of an army rifle of the present pattern showing my invention applied thereto. Fig. 2 is a plan of Fig. 1. Fig. 3 is a local plan view on an enlarged scale of the gyratory arm on which is carried the device for holding the small targets which are to be marked when the trigger is pulled and also showing on a similar enlarged scale the means for pricking or marking the target in said holder. Fig. 4 is a view in elevation of the small target.

holder and target therein which is marked as aforesaid when the trigger is pulled. Fig. 5 is a longitudinal sectional view (on an enlarged scale) of the flexible spring joint employed between the ends of the gyratory rods.

A is the gyratory arm or rod carrying the sub-target holder B at one end and connected at the other end A' to the end C' of an intermediate gyratory rod C which latter at its other end C² is jointed at D' (by a yieldable or flexible joint such as hereinafter described) to the long rod or connection D (which may advantageously be a small tube) leading from the gun to, or near, or toward, the target proper Z. The gyratory arm A may be mounted in a ball and socket bearing or any equivalent or suitable joint or bearing such for example as the "gimbal" joint a (as illustrated) in the bracket E fixed to and carried by the stock of the gun Y; a sectional view on an enlarged scale of such gimbal joint being shown in detail in Fig. 3 in which a is the spherical ball fixed on the rod A and pivoted in the concave socket or bearing or support e which latter is pivoted in turn (as a gimbal) in the bracket E so that the rod A can turn in any direction or this bearing or point A may advantageously be of the well-known gimbal type. The end A¹ of the rod A is shown in said Fig. 3 as tubular or is formed with a recess into which is introduced the rounded end C^x on the end C¹ of the gyratory arm or rod C which latter toward the other end C² is mounted in a ball and socket joint c (or by means of a gimbal joint) in a bracket F in a similar manner to that described with reference to the gyratory rod A and the bracket E.

40 G is an intermediate bracket provided with an eye or opening through which the rod or arm C passes the size of said eye or opening in this bracket G being such as to keep the gyratory movements of the arms or rods C and A within the desired limits.

The end of the long rod or connection D is attached at the fixed point (at or near the target) in any suitable manner as for example by means of a ball and socket—or by means of a gimbal—joint (such as a) in the fixed bracket or if desired, this long rod or connection D may be arranged to slide through the joint (or point of attachment) at H in order to permit greater freedom of movement of the gun.

The various parts A C and D may advantageously be made tubular and the whole of the parts of my apparatus or as many as possible may advantageously be made of aluminum on account of its lightness. The joint D¹ may advantageously consist of a disk d¹ on the tubular end of the connection D and a disk d² on the tubular end C² of the arm or rod C and a spring d located within and fixed to said tubular ends—thus forming a yield-

ing joint between the said parts as illustrated in Fig. 5.

On the side of the rifle Y close to the end of the gyratory arm A carrying the miniature target holder B I arrange a target pricking apparatus or means for indicating on the small target which is to be marked the aim of the rifle such pricking apparatus comprising a forwardly extending needle or pointer I adjustably fixed on the arm J carried on the rod or slide K which latter is adapted to slide in the bearing or guide L fixed to the side of the rifle and the rear end K' of this rod or slide where it emerges from the guide L is interposed in the path of travel of the cocking-piece X or extension provided on the cocking-piece X (see Fig. 3) of the rifle Y this rod or slide K being normally kept pulled back rearwardly into its rearmost position by the spring M so that in this normal position 85 the needle or marker I is held clear of the target holder B and miniature target therein with the rear end K' of the rod or slide K in the path of travel of the cocking-piece X or attachment on the cocking piece as aforesaid. The cocking-piece having been drawn back the gun aimed and the trigger pulled thereupon the cocking-piece strikes the end K' of the slide K and drives the needle or marker I against the miniature target N in 95 the target holder B and marks said target N and is then instantly withdrawn by the action of the spring M.

The operation is as follows:—The gun—having been cocked—is raised to the shoulder and aim taken at the target proper Z and as the muzzle of the rifle is gyrated in taking aim it will readily be seen that this will result in the connection D imparting gyratory motion to the rod or arm C which in turn imparts gyratory motion to the arm or rod A and thereby gyratory motion is imparted to the target holder B corresponding (either equal or increased or diminished as desired) to the gyratory motion of muzzle of the rifle 110 and thus if at the moment of pulling the trigger the rifle is actually and truly aimed at the bull's-eye at said moment the target holder B will have brought the bull's-eye on the miniature target N exactly opposite the needle or 115 marker I and consequently the release of the hammer by pulling the trigger at this moment will cause the miniature target N to be marked on the bull's-eye while if the aim of the rifle happens to be at any other part of 120 the target proper then the corresponding part of the miniature target will be brought opposite the marker and marked at such point when the trigger is pulled.

Various modifications may obviously be 125 employed in carrying out my invention as for example:—The gyratory rod A and bearing E might be dispensed with and the rod C lengthened and terminating in a point (adapted to serve as a marker or pricker) at 130

- about the position of the rearmost end of the rod A while in such case the target holder B would be mounted on the bracket J in place of the pricker or marker I. If desired a lens or lenses might be fixed on the gun so that, in sighting or aiming the gun the target proper would be viewed through such lens or lenses and thus made to appear at a greater distance than the actual distance. A stand 5 may advantageously be provided for the rifle or gun to rest in when out of use in order to prevent the apparatus being strained by the rifle being pointed or turned too far off the target when out of use.
- 10 I am aware that in the specification of patents of prior date it has been proposed to employ a string or cord extending from the gun to the target in conjunction with means for recording the aim on a miniature target 15 carried on the gun and I neither use nor claim such string or cord.
- 20 Having now particularly described and ascertained the nature of my said invention and in what manner the same is to be performed I declare that what I claim is:—

- 25 1. The combination with a gun, of a gyratory rod mounted and supported on the same so as to lie normally parallel with the barrel of said gun; a bracket fixed to said gun and supporting said gyratory rod; means connecting said rod and the target; a mark receiving means on the rear end of said gyratory rod; and means operated when the trigger is pulled to record the aim on said mark 30 receiving means, substantially as described.
- 35 2. The combination with a gun, of a plurality of brackets mounted on the same; gyratory rods supported in said brackets in

suchwise as to permit the same to gyrate at each end; a connection flexibly jointed to one 40 of said rods and extending to the target; a miniature target holder carried by one of said gyratory rods; and a marking device so mounted on the gun stock as to be adapted to be impelled against the said miniature 45 target when the trigger is pulled, substantially as described.

3. The combination with a gun, of a plurality of rods parallel with the barrel of the same and connected together by flexible 50 joints; supports carried by said gun providing a universal motion for each of said rods; a miniature target carried by one of said rods; and means under the control of the trigger for recording the aim on said target, comprising 55 a guide way carried by the gun; a sliding rod in said guide way; and means for normally holding said rod in its retracted position, substantially as described.

4. The combination with a gun having a 60 trigger, of a plurality of flexible jointed rods; supports carried by the gun in which said rods are mounted; another rod connected to one 65 of said rods and to the target to be aimed at; a miniature target carried by another of said rods; a marking device supported by said gun; and connections between the said device and the trigger, substantially as described.

In witness whereof I have hereunto set my 70 hand in presence of two witnesses.

JOHN B. BOLITHO.
